UNITED STATES PATENT OFFICE.

OSCAR R. ENGELMANN, OF PATERSON, WILLIAM M. ENGELMANN, OF BELLEVILLE,
AND WILLIAM J. CURRIE, OF PATERSON, NEW JERSEY.

STOP MOTION FOR LOOMS.

Application filed July 17, 1924. Serial No. 726,442.

To all whom it may concern:

Be it known that we, OSCAR R. ENGELMANN, WILLIAM M. ENGELMANN, and WILLIAM J. CURRIE, citizens of the United States of America, residing at Paterson, New Jersey, Belleville, New Jersey, and Paterson, New Jersey, respectively, have invented new and useful Improvements in Stop Motions for Looms, of which the following is a specification.

This invention relates to a new or improved stop motion for ribbon looms and has for its object to produce a simple and inexpensive, yet efficient device for this purpose.

The main object of the invention is to provide means whereby on the loosening up or breaking of one or more of the ribbons being woven in the loom the latter will be immediately brought to a stop, thus avoiding the confusion, and loss of time and labor at present involved when such a loosening up or "smash" occurs.

In the accompanying drawings which illustrate the preferred embodiment of the invention:

Figure 1 is a side elevation of so much of one form of a loom as is necessary to show the location of the present stop motion;

Fig. 2 is a side elevation on an enlarged scale of part of Fig. 1 showing the present invention applied thereto;

Fig. 3 is a plan view of Fig. 2;

Fig. 4 is a front elevation of Fig. 3;

Fig. 5 is a cross-section taken on the line 5—5 of Fig. 3 looking in the direction of the arrows; and,

Fig. 6 is a plan view of a detail.

In the several figures of the drawings, the numeral 1 indicates certain portions of the framework of a ribbon loom, which may be of any desirable approved type; 2 indicates the breast piece; 3 the batten which, through the instrumentality of appropriate mechanism, is adapted to be oscillated toward and away from the breast piece 2 in the usual manner; 4 indicates a pivoted bar or rod carrying the batten 3, which in turn is carried by an upstanding arm 5 attached to or forming a part of the framework 1 of the loom; 6 indicates the shuttle mechanism of the loom, which is carried by the batten 3 in the usual manner; 7 indicates the ribbons being woven; and 8 the handle for starting and stopping the loom, which handle is

shown in the form of a bar mounted with capability of longitudinal movement in either direction on the front face of the breast piece 2. This bar is of course connected in the usual manner with the belt-shifter or other equivalent control mechanism, but such connection is not shown in the drawings as it forms no part of the present invention and will be readily understood by those skilled in the art.

With this explanation of the well-known parts of a ribbon loom, we will now proceed and describe the construction and operation of the stop mechanism, the subject-matter of the present invention.

To the front face of the batten 3 and extending across the width of the loom there is mounted to revolve in bearings 9 a spindle 10. To this spindle is secured a trip or catch in the form of an arc-shaped member 11 (see Fig. 5) which, as shown in said figure is preferably shaped at its lower end to loosely encircle the spindle 10 and then be secured thereto by a set screw 12. It is to be observed that the upper edge of the catch 11 does not contact with the front face of the batten 3, except at the extreme right (see Fig. 3), where it is provided with an integral extension 13, serving the purpose hereinafter to be described. To one end of said extension is connected a spring 14, the other end of which is connected to the batten 3.

To the underside of the breast piece 2 is fixed a rod 15 which extends across the width of the loom and on this rod are loosely mounted a plurality of hook-like members 16, one for each ribbon. These hook-like members 16 are each provided with a short laterally projecting roller 19 which is adapted in the normal operation of the machine to rest against the ribbon 7, in which position the hook is so suspended that in the oscillation of the batten 3 it will not interfere with the catch 11. Each roller 19 is mounted and free to rotate on a pin 20 fixed to and projecting from its hook 16, and the outer end thereof is bent (as shown in Fig. 6) so that the hook is prevented from moving in one direction on the rod 15 by one edge of the ribbon contacting therewith and in the other direction by the opposite edge of the ribbon engaging one side of the hook itself. Below the rollers 19 there is arranged a stop rod 22 extending across the

machine and fixed to the breast piece 2 as by brackets 23. As will be seen from Fig. 2, the ribbon 7 after passing the roller 19 is continued down on the breast piece side 5 of said rod and then down to the usual sand rollers 24. The rod 22 is provided for the treble purpose of providing an angular deflection of the ribbon so as to form a convenient "rest" for the hook 16; to act as a 10 stop to prevent any of the hooks dropping too far down when their ribbon loosens or breaks, and for preventing the loom operator from accidentally interfering with the hooks 16 while "letting back" any individual 15 ribbon, an operation well known in the art and which is accomplished from the underside of the breast piece 2.

Fixed to the frame of the machine at one 20 end thereof is a stub shaft 25 on which is pivoted a fork-like member 26 provided with two spaced-apart downwardly-extending fingers 27. The inner end of the member 26 underlies a finger 28 fixed to and projecting from the spindle 10, and a 25 spring 29 connected thereto and to the underside of the breast piece.

Also fixed to the underside of the breast 30 piece 2 is a tube or pipe 30 which, for a portion of its length, is provided at both sides 35 thereof with a slot 31. Within the tube 30 is positioned a spring 32, one end of which is connected to the pipe and the other end to a cross bar 33 working within the pipe and projecting transversely therefrom through the slots 31.

Fixed to the starting and stopping bar 8 is a downwardly projecting right-angle member 35, the horizontal portion of which is provided with two up-standing spaced-apart fingers 36. As will be clearly seen 40 from Fig. 2, these fingers are spaced apart at a distance greater than the fingers 27 of the member 26, but the distance between them is less than the length of the cross bar 33.

45 The operation of the above-described mechanism may be briefly described as follows:

In the normal operation of the machine the 50 fingers 27 of the member 26 extend down between the cross piece 33 and the fingers 36 of the member 35 (see Fig. 4). In this position the spring 32 is extended so that when the fingers 27 are raised as hereinafter described, the cross piece 33 will fly back under 55 the influence of the spring, strike the fingers 36 of the piece 35, and in turn operate the handle 8 to stop the machine. The lifting of the fingers 27 is effected as follows:

Should any one of the ribbons 7 slacken 60 or break, the corresponding hook 16 at once drops as it is no longer held suspended in its upper position by the normal tension of the ribbon. Said hook will thus engage the catch 11 and as this latter is reciprocating 65 with the batten 3 said catch will be pulled

down on the outward movement of the latter turning the spindle 10 and in turn lowering the trip 28 into contact with the inner end of the finger piece 26. This end is consequently depressed while, of course, the 70 opposite end carrying the two fingers 27 is raised as shown in dotted lines in Fig. 2, with the result hereinbefore indicated. The spring 29 returns the finger piece 26 promptly to its normal position.

75 After the necessary adjustment has been made to the loom the stop motion is quickly re-set by operating the handle 8 in the usual manner to start the loom, that is to say, by moving it to the left with respect to 80 the drawings. This movement will cause the fingers 36 to engage the cross bar 33 and carry it to the left stressing the spring until the fingers 27 are encountered. As 85 shown in Fig. 4, the fingers 27 are beveled at their lower ends on the inner side thereof so that in the motion of re-setting when they are encountered by the bar 33 they will rise slightly to permit the bar to pass thereunder and then drop back again under the influence of spring 29, thus locking the bar in its 90 set position.

95 Regarding the extension 13 and the spring 14, these are provided so that in the normal operation of the machine the spindle 10 and the catch 11 carried thereby are held in proper position for engagement by the hooks 16. The said catch 11 is formed arc-shaped so that should for any reason a 100 ribbon slacken or break and its controlling hook accordingly drop when the batten in its movement is so far away from the breast piece that the hook when it drops does not fall so as to engage the catch 11, then, on the next movement of the batten toward the breast piece, on the said hook encountering the catch 11 it will ride up the face of said member, drop into position and then, on the next movement of the batten away from the breast piece, will pull the catch 11 down and turn the spindle 10 as hereinbefore described. The hook is, of course, also 105 shaped to facilitate this operation.

110 It will be understood that the stop motion hereinbefore described, and shown in the drawings, is merely the preferred embodiment thereof and various changes may be made therein without departing from the spirit and scope of the invention.

115 Having now described our invention what we claim and desire to secure by Letters Patent is:

120 1. In a stop motion for ribbon looms having a batten and a breast piece, a plurality of ribbon-controlled hooks carried by the breast piece, and means carried by the batten for automatically effecting the stoppage of the loom on the release of a hook by its ribbon.

125 2. A stop motion for ribbon looms having

a batten and a breast piece, comprising a trip piece carried by the batten, a plurality of hooks carried by the breast piece, the engagement of which with the trip is controlled by the tension of the ribbons being woven, and means for automatically bringing the loom to a stop on the engagement of a hook with the trip.

3. A stop motion for ribbon looms having a batten and a breast piece, comprising a trip piece carried by the batten, a plurality of hooks carried by the breast piece, the engagement or non-engagement of each of which with the trip is controlled by the tension of a ribbon being woven, and means operated by said trip piece for bringing the loom to rest on such engagement taking place.

4. In a ribbon loom provided with a batten, a stop motion comprising a trip piece carried by and oscillating with the batten, a hook held suspended by the ribbon being woven clear of said trip piece during the normal operation of the loom but which on the ribbon slackening or breaking will fall so as to engage said trip, and means for automatically stopping the loom on such falling of the hook.

5. A stop motion for ribbon looms having a batten and a breast piece comprising a trip piece carried by the batten, a plurality of hooks carried by the breast piece and held suspended by the ribbons being woven clear of said trip piece during the normal operation of the loom, a fork-like member pivoted to the frame of the loom, a cross bar locked under tension by said fork-like member during the normal operation of the loom, and a finger piece carried by the trip piece adapted on the slackening or breaking of a ribbon and the fall of its hook into engagement with the trip piece to raise said fork-like member to release the cross bar and bring the loom to rest.

45 6. A stop motion for ribbon looms having a batten and a breast piece, comprising a trip piece carried by the batten, a plurality of hooks carried by the breast piece and held suspended by the ribbons being woven clear of said trip piece during the normal operation of the loom, a fork-like member pivoted to the frame of the loom, a cross bar locked under tension by said fork-like member during the normal operation of the loom and a finger piece carried by the trip piece adapted on the slackening or breaking of a ribbon and the fall of its hook into engagement with the trip piece to raise said fork-like member to release the cross bar and bring the loom to rest, said trip piece being arc-shaped in cross section and the hooks being co-operantly shaped so that should the hook drop when the batten is so far out in its movement that said hook cannot engage the trip piece, then on the

next movement of the batten toward the breast piece the hook will ride up the face of said piece into engagement therewith.

7. A stop motion for ribbon looms having a batten and a breast piece, comprising a trip piece carried by the batten, a plurality of hooks carried by the breast piece, the engagement of which with the trip is controlled by the tension of the ribbons being woven, means for automatically bringing the loom to a stop on the engagement of a hook with the trip, and a stop rod disposed beneath said hooks, for the purposes stated.

8. In a stop motion for ribbon looms having a batten and a breast piece, a trip piece carried by the batten, a rod secured to the breast piece, a plurality of hooks pivoted on said rod, and means operated by said trip piece for bringing the loom to rest on the engagement of a hook with the trip piece, the engagement or non-engagement of the hooks with the trip piece and their position on the rod being controlled by the ribbons.

9. In a stop motion for ribbon looms having a batten and a breast piece, a spindle attached to the breast piece, an arc-shaped trip piece carried by said spindle, a rod secured to the under side of the breast piece, a plurality of hooks pivoted on said rod in line with the ribbons being woven, a laterally-extending roller on each hook adapted to contact with its ribbon to hold the hook, in the normal operation of the machine, out of engagement with the trip piece, a finger carried by said first-mentioned rod, and means operated by said finger on the falling of a hook into engagement with the trip piece, by the slackening or the breaking of its ribbon, to automatically bring the loom to rest.

10. In a stop motion for ribbon looms a fork-like member pivoted to the frame of the loom, a pair of spaced-apart fingers depending therefrom, a right angle member carried by the usual starting and stopping handle of the loom, a pair of up-standing fingers on said latter member, a split tube fixed to the frame of the loom between said two pairs of fingers, a spring within said tube, a cross bar connected to one end of said spring, said second pair of fingers being spaced apart at a distance greater than said first mentioned pair of fingers but less than the length of the cross bar, and said first mentioned pair of fingers acting to lock the cross bar under tension during the normal operation of the loom, and means operated by the ribbons being woven for releasing said cross bar to bring the loom to rest on the slackening or breaking of a ribbon.

11. In a ribbon loom provided with a batten and a breast piece, a stop motion comprising a trip piece carried by and oscillating with the batten, a finger secured to

and projecting from said trip, a plurality of hooks, one for each ribbon being woven, carried by the breast piece, a roller on each hook adapted to contact with a ribbon and 5 hold the hook suspended clear of the trip piece when the ribbon is taut but which will permit the hook to fall into the path of the trip on the slackening or breaking of the ribbon, a hook-like member pivoted to the 10 frame of the loom with its inner end underlying the finger on the trip, a pair of spaced-apart fingers depending from said member, a right angle member secured to the usual operating handle of the loom, a pair of 15 spaced-apart fingers upstanding from said latter member, a split tube, a cross piece pro-

jecting transversely therefrom, and a spring within said tube having one end connected to said cross piece and the other end to the tube, said first-mentioned fingers acting to 20 lock the cross piece with the spring under tension during the normal operation of the loom but which fingers on the slackening or smashing of the ribbon will be raised by the trip to release the cross piece and stop the 25 loom.

In testimony whereof we have signed our names to this specification.

OSCAR R. ENGELMANN.
WILLIAM M. ENGELMANN.
WILLIAM J. CURRIE.
